UNITED STATES PATENT OFFICE

GUSTAVE BLUEMEL, OF CHICAGO, ILLINOIS, ASSIGNOR TO DRYING SYSTEMS, INC., OF
CHICAGO, ILLINOIS, A CORPORATION OF ILLINOIS

HEATER

Application filed January 13, 1930. Serial No. 420,545.

This invention relates to heaters for air and other gases and particularly to those in which the air or gas is mixed with products of combustion for use as a heating medium, as in industrial drying and heat treating.

The main objects of this invention are to provide an improved form of heater for air and gases that are propelled or drawn along by a blower or the like whereby the flow of such air or gas is utilized for inducing a flow of products of combustion through a burner forming a part of said heater; to provide improved means for controlling the portions of the products of combustion to the air or other gas to be heated; to provide a device of this kind which may be readily connected into an air or gas duct so as to form a part thereof and utilize the current of air through said duct regardless of the position of the blower with respect to said heater; to provide a heater of this kind which is universally adaptable either as a "pull through" or "push through" type, and which may utilize fluid fuel burners either of the atmospheric pressure type or high pressure inspirator type; and to provide improved means for controlling the suction for inducing the flow of products of combustion and for preventing back pressure on the combustion chamber.

A specific embodiment of this invention is illustrated in the accompanying drawings, in which:

Figure 1 is a longitudinal section of the improved heater equipped with a burner of the atmospheric pressure type.

Fig. 2 is a side elevation of the same.

Fig. 3 is an end elevation viewed from the right of Fig. 1.

Fig. 4 is a section taken on the line 4-4 of Fig. 1.

Fig. 5 is a diagrammatic view in side elevation, showing the relationship between the air blower and the combustion device.

In the form shown in the drawings, the heater is shown equipped with a so-called atmospheric type of burner, namely, one in which the air is taken directly from the atmosphere, as in the usual Bunsen burner, but

it will be understood that this invention is not limited to any particular type of burner, but is equally applicable to any form of burner and to liquid, gaseous, or powdered fuel employing any of the well-known methods of mixing air and fuel to produce combustion in the combustion chamber and supply the desired quantity of products of combustion for mixture with air or other gas as a heating medium. The device is also universal in its application to the extent that it will operate equally well in any position in which it is connected to a system of ducts; that is to say, the burner may be located either at the top or at either side or the bottom, as may be desired.

The burner shown comprises a primary mixer 1, having a gas supply pipe 2 and air inlet 3, and the combustion chamber is supplied with a secondary air inlet 4 in which the gas pilot 5 may be conveniently located. The combustion chamber 6 is formed within an L-shaped fitting 7, lined with firebrick 8 or other suitable refractory material. The outlet 9 of the combustion chamber may be circular and is preferably flared both internally and externally.

Symmetrically arranged around the outlet end of the combustion chamber is a tubular housing 10, preferably cylindrical in its interior, and the ends of said housing are provided with flanges 11 and 12 for connection with a blower housing or with duct-work, and it will be readily understood that a blower or fan might be connected at either end of the housing 10 as the engineer might elect, for the purpose of causing the air or other medium that is to be heated to flow through the housing in the direction of the arrows.

The housing comprises an outer supporting shell and a sleeve 13 is mounted to slide longitudinally within the outer shell and shaped to form a Venturi passage concentric with the flared end of the tubular outlet of the combustion chamber. The sleeve 13 has a contracted throat 14 substantially equal to or slightly greater in diameter than the external diameter of the rim 15 of the flared walls of the outlet 9 from the combustion chamber.

- The sleeve 13 may be adjusted by means of an adjusting screw 16 to vary the area of the passage between the throat 14 and the externally flared wall 17 of the combustion chamber. This adjustment is accomplished by means of a nut 18, seated in a pocket in a hollow member 19, which is mounted on the housing 10 and is open at the top to provide access to the nut 18. Said open top is closed by a plate or lid 20 which may be screwed into place after the adjustment is made for any desired set of conditions.
- In order to insure a high degree of efficiency in the combustion of the fuel before it mixes with the air at the throat of the Venturi sleeve, a conical mass of refractory material 21 is mounted opposite the outlet end of the combustion chamber where it will become incandescent and baffle the products of combustion so as to cause them to flow annularly outward under the eductive action of the air current through the Venturi passage. The baffle 21 is preferably provided with a concave heat reflecting and radiating surface 22 facing the combustion chamber 6 and is tapered to approximately a stream line form and mounted in a conical ring 23 carried by spider arms 24 extending to a ring 25 bolted to the housing.
- The main shell of the housing is surrounded by a rectangular jacket 26 spaced from the walls of the housing, said space being filled with asbestos or any other suitable insulating material 27. The shell 10 and sleeve 13 have registering side openings or slots 28 and 29 respectively, through which the flame at the outlet may be observed. This opening is closed against air inflow or gas outflow by means of a plate of glass 30.
- The operation of the device shown is as follows:
- A blower 31 (Fig. 5), has its delivery outlet bolted directly to the end of the housing which is at the left of Figure 1 or is connected thereto by a duct, and forces an air current through the housing so as to traverse the throat 14 of the Venturi sleeve as indicated by arrows in Figure 1. It will be understood, however, that while the blower is preferably located at the left of Figure 1, it may with similar effect be connected to withdraw air at the right, the two types of assembly being known in the art as the "push-through" and "pull-through" types respectively. Gaseous fuel and air are supplied to the combustion chamber 6 at its inlet end which is at the bottom of Figure 1, and are burned in the combustion chamber. The air flowing through the housing and Venturi sleeve attains a high velocity in the throat of the venturi and on expanding produces partial vacuum which draws the products of combustion over the rim of the baffle 21 where they mix with this air. The refractory walls of the combustion chamber and baffle become

incandescent and promote complete combustion.

Adjustment is made for desired conditions by means of the nut 18 which shifts the sleeve 13 while the operator is observing the flame 70 through the side opening 28.

Although but one specific embodiment of this invention has been herein shown and described, it will be understood that details of the construction may be altered or omitted 75 without departing from the spirit of this invention as defined by the following claims:

I claim:

1. A heater comprising a combustion chamber having fuel and air inlets and an 80 outlet, housing means providing an air passage surrounding said outlet, a sleeve in said passage having a throat for restricting said passage in the vicinity of said outlet, said sleeve being of enlarged sectional area beyond 85 said outlet for producing an expanding air current and thereby inducing the flow of products of combustion from said outlet.

2. A heater comprising a combustion chamber having fuel and air inlets and an outlet, 90 housing means providing an air passage surrounding said outlet, a sleeve in said passage having a throat for restricting said passage in the vicinity of said outlet, said sleeve being of enlarged sectional area beyond said outlet 95 for producing an expanding air current and thereby inducing the flow of products of combustion from said outlet, said outlet having a flared mouth opposed to the throat of said sleeve, and means for shifting said sleeve longitudinally to vary the velocity of the air in said throat.

3. A heater comprising a combustion chamber having fuel and air inlets and an outlet, 105 housing means providing an air passage surrounding said outlet, a sleeve in said passage having a throat for restricting said passage in the vicinity of said outlet, said sleeve being of enlarged sectional area beyond said outlet 110 for producing an expanding air current and thereby inducing the flow of products of combustion from said outlet; and a heat retaining baffle located in line with said outlet.

4. A heater comprising a combustion 115 chamber having fuel and air inlets and an outlet, housing means providing an air passage surrounding said outlet, a sleeve in said passage having a throat for restricting said passage in the vicinity of said outlet, said 120 sleeve being of enlarged sectional area beyond said outlet for producing an expanding air current and thereby inducing the flow of products of combustion from said outlet, and means connected with said housing for caus- 125 ing air to flow through said sleeve.

5. A heater comprising a burner having an L-shaped combustion chamber, fuel and air inlets in one branch of said chamber, an outlet at the end of the other branch, said com- 130

bustion chamber having outwardly flared walls adjacent said outlet, a sleeve surrounding said outlet and having a Venturi passage therethrough, a housing surrounding said sleeve and forming an air passage for directing a current of air through said Venturi passage, said Venturi passage including a contracted throat, and means for shifting said sleeve longitudinally of the outlet branch of said combustion chamber to vary the area of the air passage between said throat and flared outlet.

6. A heater comprising a gas burner, a combustion chamber having fuel and air inlets and a flared outlet, housing means providing an air passage surrounding said combustion chamber, an adjustable sleeve in said passage having a throat for restricting said passage, a heat retaining cone opposed to 10 said flared outlet, said cone having an outer shape in such relation to the diameter of the flare of said outlet that a Venturi effect will be created to cause the withdrawal of the products of combustion from said outlet and 15 their mixing with the inducing air currents, and means connected with said housing for 20 causing air to flow through said sleeve.

7. A heater having surrounding walls forming a mixing chamber for air and 25 products of combustion, a combustion device having an outlet to said mixing chamber, a refractory member mounted in the mixing chamber opposite the outlet of the combustion device, said surrounding walls and said 30 combustion device being formed to provide a Venturi passageway surrounding the outlet of said combustion device, and a blower having connections to said Venturi air passageway for forcing air into the mixing 35 chamber and inducing a flow of the products of combustion through said outlet.

40 Signed at Chicago this 9th day of January,
1930.

GUSTAVE BLUEMEL.
